UNITED STATES PATENT OFFICE.

ARTHUR J. LANG, OF BROOKLYN, NEW YORK.

TUNING-BUTTON.

SPECIFICATION forming part of Letters Patent No. 675,742, dated June 4, 1901.

Application filed March 25, 1901. Serial No. 52,686. (No model.)

To all whom it may concern:

Be it known that I, ARTHUR J. LANG, a citizen of the United States, and a resident of the city of New York, borough of Brooklyn, in the county of Kings and State of New York, have invented a new and Improved Tuning-Button, of which the following is a full, clear, and exact description.

My invention relates to that class of tuning-buttons which are used at the neck-section of stringed musical instruments.

The purpose of the invention is to provide such a tuning-button with a light yet durable metal head and to firmly secure such a head on the stem or shank of the button in an expeditious, effective, and simple manner.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of one section of the head. Fig. 2 is a perspective view of the second or opposing section of the head. Fig. 3 is a transverse section through the stem or shank of the button and its head, showing the two sections of the head connected. Fig. 4 is a longitudinal section through the head and a side elevation of the shank or stem of the button, and Fig. 5 is an enlarged cross-section through the stem or shank and through the completed and shaped head of the button.

The device consists, primarily, of three parts—two cap-plates A and B, which are adapted to be brought together, and a stem or shank C, an end of which is to occupy a position between the cap-plates. The stem or shank is provided between its ends with an annular groove 11, and in the drawings the stem or shank C is shown as provided with the usual exterior thread employed in connection with screw-buttons.

The section A, which is shown in detail in Fig. 1, consists of a circular cap-plate 12 and a marginal flange 13, in which flange a recess 14 is produced. Both of the sections A and B are constructed from light or sheet metal, such as brass. The section B of the head comprises likewise a cap-plate 15 and a mar-

ginal flange 16; but this flange 16 is offset from the cap-plate, forming an annular shoulder 17 where the cap-plate and its flange connect, and the flange 16 of the section B is provided with a slot or recess 18, which extends usually to the cap-plate. The flange 16 of the section B is of less circumference than that of the flange 13 of the section A, since the flange 16 of the section B is to telescope within the flange of the opposing section A when the two parts are brought together.

Before the two parts or sections A and B are brought together the plain end of the stem or shank C is made to enter the section A at the recess 14, and the side walls of this recess fit into the annular groove 11 in the stem or shank, as is illustrated in Fig. 4. The opposing section B of the head is now placed within the section A, the slot or recess 18 in the section B receiving the shank, permitting the two cap-plates of the two sections to lie in close engagement with opposite sides of the shank or stem, as is clearly shown in Figs. 3, 4, and 5. Next the free edge of the flange 13 of the head-section A is bent inward to fit the shouldered portion 17 of the opposing section B, as is shown also in Figs. 3, 4, and 5, filling the space which was made to produce the shoulder, and when the flange of the section A is thus bent or crimped upon the outer section B the outer face of the cap-plate 15 of the section B will be substantially flush with the outer face of the bent or crimped portion of the flange of the opposing section. The two sections of the head now firmly engage with the stem, and the completed head is then rolled so as to produce the concaved faces 19 (shown in Fig. 5) in both cap-plates at opposite sides of the shank. When the head is so rolled, its outer edges are of less transverse thickness than its central portion, while the central portion of the head clings securely to the stem or shank. This curvature is imparted to the head in order to render said head more conveniently gripped between the thumb and fingers, and is also present in the usual heads made of wood, celluloid, and the like.

The main purpose of this invention is to provide not only an inexpensive head and one which may be rendered highly ornamental, but also to provide a head which will not

check, split, or break when subjected to sudden blows.

Having thus described my invention, I claim as new and desire to secure by Letters

5 Patent—

1. In a tuning-button, a head therefor, consisting of opposing cap-plates each provided with a marginal flange, the flange of one cap-plate being offset to extend beyond the cap-plate, the said flange being adapted to telescope within the opposing section, the flange of each section of the head being provided with recesses therein adapted to register, the free edge of the flange of the outer section of the head being bent inward to engage with the shoulder formed by the offset of the flange of the smaller or opposing section of the head.
2. In a tuning-button, a stem or shank and a head constructed of metal in two sections, each section comprising a cap-plate and a flange, the flange of one section being adapted to enter the flange of the opposing section, the flanges of both sections having openings to receive the stem or shank, the flange of the smaller section being offset, extending out beyond the cap-plate of said section,

forming an annular space above a shoulder, into which space the free edge of the flange of the larger head-section is bent or crimped, as set forth.

3. In a tuning-button, the combination, with a stem or shank provided with a circumferential groove, of a head consisting of two metal sections, each section comprising a cap-plate and a marginal flange, each flange having a recess therein, one section being smaller than the other and adapted to enter the larger section, the walls of the recess in the flange of the larger section entering the groove in the stem or shank, the smaller section being provided with an annular depression where its flange connects with the cap-plate, into which depression the free edge of the flange of the larger section is bent and secured, as described.

In testimony whereof I have signed my name to this specification in the presence of two subscribing witnesses.

ARTHUR J. LANG.
